UNITED STATES PATENT OFFICE.

ARMAND LEGÉR, OF FENTON, ENGLAND, ASSIGNOR TO T. C. BROWN-WESTHEAD, MOORE & CO., OF STOKE-UPON-TRENT, ENGLAND.

DESIGN FOR A PLATE OR SIMILAR ARTICLE.

SPECIFICATION forming part of Design No. 26,761, dated March 16, 1897.

Application filed October 16, 1896. Serial No. 609,156. Term of patent 7 years.

To all whom it may concern:

Be it known that I, ARMAND LEGÉR, a subject of the Queen of Great Britain, residing at Fenton, Stoke-upon-Trent, England, have 5 invented and produced a new and original Design for Plates or Similar Articles, of which the following is a specification, reference being had to the accompanying drawings, forming part thereof.

10 In said drawings, Figure 1 is a reduced view of my complete design, the elementary parts of which are repeated a number of times to form a circular design located upon the border or rim of the plate or other similar article. 15 Fig. 2 is a segmental portion of the design, showing the elementary parts on a larger scale.

The leading feature of my design is found in the border, comprising a fanciful flower having 20 six petals, the stamen or center portion

being five-branched and terminating in knob-like protuberances. The flower may be said to be "arabesque" in fashion.

The flowers are arranged at regular intervals in a circular wreath, and extending between the flowers are the stems curving inwardly and outwardly and ornamented with series of arabesque cup-shaped parts and variously-shaped leaves of gradually-increasing size. The series of cup-shaped parts and leaves follow each other alternately in the wreath. 25 30

I claim—

The design for plates or similar articles, substantially as herein described.

ARMAND LEGÉR.
